Patented Apr. 14, 1914

UNITED STATES PATENT OFFICE.

BURNHAM C. STICKNEY, OF ELIZABETH, NEW JERSEY, ASSIGNOR TO JOHN T. UNDERWOOD, OF BROOKLYN, NEW YORK.

TYPE-WRITING MACHINE.

1,093,298.

Specification of Letters Patent.

Patented Apr. 14, 1914.

Application filed March 5, 1912. Serial No. 681,744.

To all whom it may concern:

Be it known that I, BURNHAM C. STICKNEY, a citizen of the United States, residing in Elizabeth, in the county of Union and 5 State of New Jersey, have invented certain new and useful Improvements in Type-Writing Machines, of which the following is a specification.

This invention relates to means for feeding webs to the feeding-rolls of typewriters and other printing-machines, etc.

I support upon the table or framework of the machine a swinging frame, which has a connection to the carriage of the typewriter 15 or printing-machine, so as to swing as the carriage travels. The roll or rolls of paper are mounted on said swinging frame at points near the hinge or pivot thereof, so that there is very little movement of said 20 rolls at the letter feeding movement of the carriage, and hence the inertia of the rolls is not so serious an objection to the rapid operation of the machine as heretofore. The webs are led from the rolls upwardly and 25 looped over an inclined guide mounted on said swinging frame, and are thence led to the rolls of the typewriter. The inclined guide is preferably mounted to swing independently of the carriage, so as always to 30 substantially take up the slack in the web.

In the accompanying drawings, Figure 1 is a rear view of an Underwood typewriting machine, showing my improvements connected thereto. Fig. 2 is a plan of a hinged 35 frame upon which the paper rolls or spools are mounted. Fig. 3 is a part-sectional elevation, showing the relation of my improved device to the typewriting machine.

The frame 1 of the typewriting machine 40 rests upon a table 2. A carriage 3, having a cylindrical platen or roll 4, travels upon tracks, of which one is seen at 5. The web is fed around the platen by the usual rolls 6, 7. The letter-feeding movement of the carriage 45 is controlled by a mechanism of which a part is seen at 8. A roll or spool of paper 9 is pivoted at 10 to a frame 11, which is hinged or pivoted at 12 in a stationary bracket or support 13, resting upon the table 2 back of 50 the typewriting machine and close thereto. The hinged frame 11 has an arm or arms 14, carrying a web 15 to receive carbon imprints of the typewritten matter; and a carbon roll

16 may be mounted upon an arm or arms 17, the carbon web being laid between the webs 55 15 and 9, thus forming a multiple web which is looped over a guide 18 and led down to the bight of the rolls 4, 6. The three webs are preferably assembled or passed between guide pins 19 on said arm or arms 14. The 60 guide 18 may be in the form of a roll journaled upon a long pin or stud 20 projecting from a boss 21 formed upon the upper end of arm 22, which extends up from the frame 11; and this arm may be connected by a link 65 22^a to an arm 22^b, which is fixed upon the carriage 3, so that the roll-carrying frame will swing or vibrate upon the hinge 12 as the carriage moves to and fro; the travel of the carriage being generally less than the 70 width of the web 9. It will be seen that the guide 18 is inclined upwardly, forwardly and sidewise from the arm or standard 22, in a position to take up the slack due to the twisting of the web from the original edge- 75 wise position at Fig. 1 to the final flatwise position at said figure, when it is wrapped around the platen. By placing said guide substantially as shown in said figure, it is practicable for the web to extend downwardly and forwardly tangentially to the platen, and vertically down to the guide pins 19. There is also permitted a sufficient range 80 of movement of the carriage to write entirely across the narrow web without danger 85 of tearing it.

Preferably the arm 22, carrying the inclined guide 18, is swiveled, and it may also be provided with an arm 23 by which it may be turned, so that the guide roll 18 can be 90 swung sidewise to accommodate the movement of the carriage and substantially take up the slack in the web at all times. This swinging of the roll is accomplished automatically; a pin 24 on said arm 23 engaging 95 a slot 25 in a plate 26, the latter fixed upon an arm 27 projecting up from the fixed bracket 13. As the carriage travels in letter-feeding direction during the writing of a line on the web, the arm 22 is caused to turn 100 slightly on its upright axis 28, so that the forward end of the guide roll 18 travels faster than the rear end, in the direction in which the carriage travels. The cam 25 may be so shaped and the guide 18 so placed that 105 substantially all of the slack in the web will

be taken up. Therefore the web will travel true, and maintain its proper relationship to the platen, without danger of slipping or of injuring its edges, or of relative displacement of the members of the three-part web.

The link 22^a is pivoted to an ear upon the arm 22, by means of a universal joint 29, so as to accommodate the swinging motion of said arm 22 produced by the cam 25.

10 Variations may be resorted to within the scope of the invention, and portions of the improvements may be used without others.

Having thus described my invention, I claim:

15 1. The combination with a typewriter carriage, of a swinging frame having a stationary support, and connected to said carriage to swing as the latter travels, means on said swinging frame for supporting a roll or spool of paper, and a guide on said swinging frame over which the web is looped in passing from the roll or spool to the typewriter carriage.

25 2. The combination with a typewriter carriage, of a swinging frame having a stationary support, and connected to said carriage to swing as the latter travels, means on said swinging frame for supporting a roll or spool of paper, and a guide on said swinging frame over which the web is looped in passing from the roll or spool to the typewriter carriage; said guide being inclined to take up the slack in the web.

35 3. The combination with a typewriter carriage, of a swinging frame having a stationary support, and connected to said carriage to swing as the latter travels, means on said swinging frame for supporting a roll or spool of paper, and a guide on said swinging frame over which the web is looped in passing from the roll or spool to the typewriter carriage; said guide being inclined laterally, upwardly and forwardly to take up the slack in the web.

45 4. The combination with a typewriter carriage, of a swinging frame having a stationary support, and connected to said carriage to swing as the latter travels, means on said swinging frame for supporting a roll or spool of paper, a guide on said swinging frame over which the web is looped in passing from the roll or spool to the typewriter carriage, said guide inclined to take up the slack in the web, and means 50 for shifting the position of said guide as the carriage travels, so that it may take up the slack in the web at all the relative positions of said carriage and swinging frame while the web is being written upon.

60 5. The combination with a typewriter carriage, of a swinging frame having a stationary support, means on said swinging frame for supporting a roll or spool of paper, a guide on said swinging frame over 65 which the web is looped in passing from the

roll or spool to the typewriter carriage, an arm connected to said carriage, and a link connecting said arm to said swinging frame.

6. The combination with a typewriter carriage, of a swinging frame having a stationary support, means on said swinging frame for supporting a roll or spool of paper, a guide on said swinging frame over which the web is looped in passing from the roll or spool to the typewriter carriage, an arm connected to said carriage, a link connecting said arm to said swinging frame, an arm upon said swinging frame, and a pin-and-slot device connected to said arm to turn the swinging frame as the latter swings upon its hinge, so as to shift the position of said guide bar or roll relative to said swinging frame.

7. The combination with a typewriter carriage, of a swinging frame for supporting a plurality of rolls of paper, so that webs leading from the several rolls may be superposed, a guide on said swinging frame over which the webs may be looped on their way to the carriage, said guide mounted to substantially take up the slack in the web, said roll-supporting means mounted close to the hinge of said swinging frame, and means connecting said swinging frame to said carriage.

8. The combination with a typewriter carriage, of a swinging frame for supporting a plurality of rolls of paper, so that webs leading from the several rolls may be superposed, a guide on said swinging frame over which the webs may be looped on their way to the carriage, said guide mounted to substantially take up the slack in the web, said roll-supporting means mounted close to the hinge of said swinging frame, and means connecting said swinging frame to said carriage; guide pins being provided upon said swinging frame for assembling and guiding said webs.

9. The combination with a typewriter carriage, of a swinging frame having a stationary support, and connected to said carriage to swing as the latter travels, means on said swinging frame for supporting a roll or spool of paper, a guide on said swinging frame over which the web is looped in passing from the roll or spool to the typewriter carriage, said guiding bar overlying said rolls at a point substantially above the platen of the typewriter, and in such position that the web extends upwardly and rearwardly directly from the typewriter platen to said bar.

10. The combination with a typewriter carriage and platen, of a swinging support, a roll of paper pivoted thereon, and a guide carried by said support, said guide located above the platen and roll, and said guide extending diagonally in such direction that a web from said roll may be led upwardly and looped diagonally, forwardly and side- 125

wise over the guide, and thence descend to the typewriter platen.

11. The combination with a typewriter carriage, of means to supply a web of paper thereto, a guide between the carriage and paper supply over which the web is guided, and means to cause said guide to move angularly with relation to said carriage and paper supply during the travel of the carriage, to take up or prevent slack in the web.

12. The combination with a typewriter carriage, of a support for a roll of paper, a guide between the carriage and support over which a web of paper extends, and means to impart an angular movement to said guide relatively to the supply roll and carriage during the travel of the latter.

13. The combination with a typewriter carriage, of a swinging frame, means on said frame to support a roll or spool of paper, a guide on said frame over which the web is looped in passing from the roll or spool to the typewriter carriage, and means to cause said guide to move angularly with relation to the supply roll and carriage during the travel of the latter.

14. The combination with a typewriter carriage, of a swinging frame adapted to support a spool or roll of paper, an upright member swiveled to said frame, a guide carried by said member over which a web of paper is adapted to be looped in extending from the roll or spool to the carriage, and means to rotate said upright member relatively to its supporting frame during the travel of the carriage.

15. The combination with a typewriter carriage, of a swinging frame adapted to support a roll or rolls of paper, an upright member swiveled to said frame, a laterally extending guide connected to said upright member, and over which webs of paper are adapted to be looped in passing from the roll or rolls to the carriage, and means to rotate said member and thereby impart an angular movement to said guide to take up or prevent slack in the webs during the travel of the carriage.

16. The combination with a typewriter carriage, of a frame adapted to support a roll of paper, a guide carried by said frame over which a web of paper is led from the roll to the carriage, and a cam device to rotate said guide relatively to both the said frame and carriage during the travel of the latter to take up or prevent slack in the web.

17. The combination with a typewriter carriage, of a swinging frame having a stationary support, means on said frame for supporting a spool or roll of paper on a horizontal axis perpendicular to the direction of travel of the carriage, an arm pivotally connected to said frame, a guide roll carried by said arm and over which a web

of paper may pass from the roll to the carriage, a connection between the carriage and said arm for swinging the arm and frame as the carriage travels, and means to impart an angular movement to said arm relatively to the frame and carriage during the travel of the latter to take up or prevent slack in the web.

18. The combination with a carriage having a revoluble platen, of a stationary support, an arm or device pivoted upon said support and connected at one end to swing with the movement of said carriage, a holder on said arm for a paper roll, said holder mounted so that the axis of the paper roll will lie in a plane at right angles to or across the axis of the platen, and a guide on said pivoted arm over which is looped the portion of the web extending from said roll to the platen, said guide extending in a direction to compensate for the difference in the direction of travel of the web from the roll to the platen.

19. The combination with a carriage having a revoluble platen, of a stationary support, an arm or device pivoted upon said support and connected at one end to swing with the movement of said carriage, a holder on said arm for a paper roll, said holder mounted so that the axis of the paper roll will lie in a plane at right angles to or across the axis of the platen, and a guide on said pivoted arm over which is looped the portion of the web extending from said roll to the platen, said guide extending in a direction to compensate for the difference in the direction of travel of the web from the roll to the platen; said roll being carried on said arm at a point thereof which moves at substantially less speed than said carriage, whereby the power applied to move said roll concomitantly with the carriage movements is substantially reduced.

20. The combination with a traveling carriage and a revoluble platen thereon, of a swinging support pivotally mounted on a stationary support, holding means for a plurality of paper rolls to support said rolls adjacent the pivot of said swinging support, and with their axes transverse to the platen axis, and a guide over which are looped portions of the webs extending from the rolls to the platen, said guide extending in a direction to compensate for the change in the direction of travel of the webs from the rolls to the platen.

21. In a typewriting machine, the combination with a traveling carriage and a revoluble platen thereon, of an arm pivotally mounted on a stationary support in rear of the platen and with its pivot transverse to the platen axis, a paper roll mounted on said arm adjacent its pivot and with its axis transverse to that of the platen, and a guide on said arm over which is looped a web ex-

tending from said roll to the platen, said guide located at a substantial distance from the pivot of said arm and movable with the carriage, said guide extending in a direction to compensate for the difference in the direction of the web where it leaves the roll and where it joins the platen.

22. In a typewriting machine, the combination with a traveling carriage and a rotary platen thereon, of a swinging support pivotally mounted on a stationary support in rear of the platen, a supply roll mounted on said swinging support below the platen, the axis of the roll being transverse to the platen axis, and a forwardly and upwardly extending guide on said support above the platen over which the web extends from the roll to the platen.

23. In a typewriting machine, the combination with a traveling carriage and a rotary platen thereon, of a swinging support pivotally mounted on a stationary support in rear of the platen, a supply roll mounted on said support below the platen, the axis of the roll transverse to the platen axis, a guide on said support above the platen over which the web extends from the

roll to the platen, said roll having its axis horizontally disposed, and said guide extending diagonally forward and upwardly 30 inclined to substantially compensate for the difference in the direction of the web where it leaves the roll and where it joins the platen.

24. In a writing machine, the combination with a traveling carriage and a rotatable platen thereon, of a swinging support pivotally mounted on a stationary support with its pivot below the platen, an arm on said support extending upwardly and provided with a guide roller above the platen, means on said support to hold a roll of paper at a point below the platen and adjacent the pivot of said support, the axis of said roll being transverse to the platen axis and said 40 guide roller extending in a direction to compensate for the change in direction of the web extending from said roll to the platen and looped over said guide roller.
